AIR CLEANER

Herbert G. Kamrath, Gastonia, N. C., assignor to
General Motors Corporation, Detroit, Mich., a
corporation of Delaware

Continuation of application, Serial No. 468,767,
December 12, 1942, which is a division of application
Serial No. 746,420, August 18, 1934.
This application, October 31, 1947, Serial No.
783,392.

13 Claims (Cl. 183-15)

1.

This invention has to do with apparatus for removing foreign matter from gases, and particularly with air cleaners for use on carburetors of internal combustion engines.

The principal object of the invention is to provide air cleaners which, without offering undue resistance to the passage of air, are capable of removing large quantities of foreign matter from it over extended periods of time without any attention or care, and when they are sated may quickly and easily be disassembled and serviced.

For a better understanding of the nature and objects of this invention, reference is made to the following specification and the accompanying drawing in which embodiments of my invention are described and illustrated.

In the accompanying drawing:

Figure 1 is a view, mainly in axial section but partly in elevation with parts broken away, of an air cleaner in which my invention is embodied.

Figure 2 is an enlarged view of a portion of the air cleaner shown in Figure 1.

Figure 3 is an axial section through half of another air cleaner in which my invention is embodied.

Figure 4 is an enlarged view of a portion of the air cleaner shown in Figure 3.

The air cleaner shown in Figures 1 and 2 includes a center tube 33 which is slotted, as at 34, to enable it to be telescoped over the air intake tube of a carburetor. The lower part of the tube 33 is enlarged to provide a shoulder 35 to prevent the tube 33 from sliding too far down on the air intake tube of the carburetor. The tube 33 extends through and is secured to the bottom of a bowl-shaped member 36 which has an oil level indicating bead 37 in its side. The side wall of this bowl-shaped member extends up only about halfway to the top of the tube 33 and has on its upper edge an outwardly extending flange 38. Seated upon the flange 38 is an inverted frusto-conical element 39 which has made integral therewith a cylindrical element 40. The inverted frusto-conical element extends down in the bowl-shaped member to slightly below the level of the bead 37. At the junction of the inverted frusto-conical and cylindrical elements of the member 39-40 there is an offset 42 which seats on the flange 38. The inverted frusto-conical element 39 and the offset 42 are imperforate but the cylindrical element 40 has in it throughout its circumference a series of rectangular air intake openings 43. The upper edge of the cylindrical element is flanged outwardly as at 44.

2.

Another inverted frusto-conical element 45, which is somewhat more steeply pitched than the inverted frusto-conical element 39, is secured to the flange 44 on the upper edge of the member 39-40 by having its rim portion doubled around the flange 44, as best shown in Figure 2. The lower edge of the inverted frusto-conical element 45 is bent upwardly to form an upright generally frusto-conical element 47 which has in it near its upper edge an inwardly directed offset whose edge makes frictional contact with the center tube 33. The inverted frusto-conical element 45 of the member 45-47 is imperforate but there are in the lower portion of the upright frusto-conical element 47 thereof a circumferentially extending series of rectangular openings 48 for the passage of air.

Above the members 39-40 and 45-47 is mounted an annular filter member 49 which consists of a shell 50 filled with filter material 51. The shell 50 consists of a single sheet of metal bent to form a hollow annular enclosure for the filter material. Near the lower outer edge of the shell the sheet is bent outwardly from the general contour of the cylindrical side of the shell and then back upon itself to form a lip portion 52 which seats upon the rim 46 of the member 45-47. In the lower and upper surfaces of the shell are formed a circumferentially extending series of radial openings 53 and 54. At its inside periphery the shell 50 fits snugly around the center tube 33 and at its outside periphery it is supported by the lip 52 which is seated on the rim 46 of the member 45-47. The members 39-40 and 45-47 and the filter member 49 are held in place by an offset portion of the cover 58 as will be more fully set forth.

Extending from within to above the center tube 33 is a member 55 shaped generally like an inverted V whose legs are secured to the center tube by rivets and which carries at its upper flattened end a bolt 56 to which the cover 58 is secured by a wing nut 57. The cover 58 is a bell-shaped member which comes down around and covers the whole air cleaner to a point somewhat below the air intake openings 43 in the member 39-40. The top of the cover is domed so that the space between it and the top of the filter member 49 increases from its periphery to its center. The upper portion of the side wall of the cover which encircles the filter member is only slightly larger in diameter than the filter member. Below this, the side wall of the cover is stepped outwardly first for a short distance only to a diameter only slightly greater than that of the lip 52 on the

filter member and then, for the remainder of its length, to a larger diameter so that this portion 60 of the cover which encircles the air intake openings 43 in the member 39-40 is spaced well outwardly therefrom. The bottom edge of the cover is rolled, as at 61, to form a reinforcing bead.

The horizontal element 59 of the upper step in the side wall of the cover is seated on the lip 52 on the filter member. Consequently, when the wing nut 57 is tightened the filter member and the members 39-40 and 45-47 are clamped firmly between the bowl-shaped member 36 and the cover and the several elements of the air cleaner are thus held firmly together. The short vertical portion of the side wall of the cover immediately below the element 59 serves to center the cover.

Before the air cleaner is put into use the annular receptacle defined by the center tube 33 and the bowl-shaped member 36 is filled with oil or some other suitable liquid 41 to the level of the bead 37 and the filter material 51 is thoroughly wetted with the same liquid.

The air cleaner shown in Figures 1 and 2 was designed to be installed on an internal combustion engine equipped with a downdraft carburetor with the enlarged portion of its center tube telescoped over the upper end of the air intake tube of the carburetor. When the air cleaner is so installed and the engine is operating air enters the air cleaner under the lower part of the cover 58, then flows through the holes 43 into the tapered channel formed between the two downwardly directed surfaces 45 and 39 which direct it toward and increase the velocity at which it strikes the surface of the oil in the sump. The air is then deflected upwardly by the oil surface, leaving in the oil the heavier dirt particles and picking up drops of oil, and then passes through the openings 48 and then 54 to contact the filter material 51 which removes the oil and the remaining dirt particles. The air, thus cleaned, then leaves the filter member through the openings 53 and passes into the center tube 33 and, thence, into the carburetor and cylinders of the engine. The oil carried up into the filter member will keep the filter material coated with oil and the dirt which is still in the air passing therethrough will adhere to the oil soaked material. The excess oil and the dirt in it will flow back to the sump by running down the slanting sides of the inverted frusto-conical element of the member 45 and out of the openings 48. The dirt will settle to the bottom of the sump and thus go out of circulation. Thus the filter material is kept wetted and washed while the engine on which the air cleaner is installed is operating. The element 47 of the member 45-47 serves to limit the amount of oil carried by the air into the filter member 49 and thus to obviate "pull-over" of oil from the air cleaner into the carburetor and engine.

To disassemble the air cleaner shown in Figures 1 and 2, the wing nut 57 is first removed which allows the cover 58 to be removed. The filter means may then be lifted from the end of the center tube 33 and cleaned. If it is desired to clean the sump also the assembly 39-40-45-47 may be removed from the body 33-36 of the air cleaner and the latter disengaged from the carburetor air intake tube and cleaned.

The modification shown in Figures 3 and 4 is similar to that shown in Figures 1 and 2 but differs from it in several respects. First, the member 39-49 has been eliminated and the bowl-shaped member modified to provide a cylindrical section in which the air intake openings 43 are

formed and an inverted frusto-conical section 62 which has approximately the same relation to the element 45 as does the element 39 in the air cleaner shown in Figures 1 and 2. Second, the lower wall of the shell of the filter member is made of woven wire screen 63 instead of sheet metal. Third, the filter member and the member 45-47 have been permanently secured together at their outer edges and the upright frusto-conical element of the member 45-47 modified at its inner edge to provide a seat for the filter member. This gives a construction which is simpler and embodies less parts.

Before the air cleaner shown in Figures 3 and 4 is put into use the annular receptacle defined by the center tube and bowl-shaped member included in it is filled with oil or some other suitable liquid to the level indicated in the drawing and the filter material 51 thoroughly wetted with the same liquid. The operation of the air cleaner shown in Figures 3 and 4 is substantially the same and its mode of disassembly similar to that of the air cleaner shown in Figures 1 and 2 except in that the member 45-47 does not have to be removed from the body separately from the filter assembly and there are, consequently, less parts to be handled.

This application is a continuation of my application Serial No. 468,767, filed December 12, 1942, which is a division of my application Serial No. 740,420, filed August 18, 1934, which has matured into Patent No. 2,304,829, dated December 15, 1942. My application Serial No. 468,767 was abandoned after this application was filed.

I claim:

1. In an air cleaner, a receptacular body, a cover for the body shaped generally like an inverted cup, a filter member which is separable from the body and the cover and disposed within the latter clamped between the outer walls of the body and the cover, and an air inlet orifice in the body below the filter member.
2. In an air cleaner, a receptacular body, a cover for the body, a member in which there is provided an air inlet orifice disposed between and separable from the body and the cover, and a filter member disposed within the cover and separable from it, the body and the first specified member.
3. In an air cleaner, a receptacular body, a cover for the body, a member in which there is provided an air inlet orifice disposed between and separable from the body and the cover, a filter member disposed within the cover and separable from it, the body and first specified member, and an inwardly and downwardly directed baffle carried by the first specified member and disposed between the filter member and the air inlet orifice.
4. In an air cleaner, a receptacular body, a cover for the body, a member in which there is provided an air inlet orifice disposed between and separable from the body and the cover, a filter member disposed within the cover and separable from it, the body and the first specified member, and an inwardly and downwardly inclined wall carried by the first specified member on each side of the air inlet orifice.

5. In an air cleaner, a receptacular body, a cover for the body, a member in which there is provided an air inlet orifice disposed between and separable from the body and the cover, a filter member disposed within the cover and separable from it, the body and first specified member, and an inwardly and downwardly in-

clined baffle with a perforate inwardly and upwardly inclined extension carried by the first specified member and disposed between the filter member and the air inlet orifice.

6. In an air cleaner, a receptacular body, air inlet and outlet orifices in the body, a filter element disposed between the air inlet and outlet orifices and above the bottom of the body, a downwardly inclined wall in the body, and a downwardly inclined baffle which is disposed between the mentioned wall and the filter element and defines with the former a passage through which air travels crosswise of the body before it enters the filter element from the air inlet orifice.

7. In an air cleaner, a receptacular member with a downwardly and inwardly inclined section in its side wall which constitutes a liquid reservoir, and a downwardly and inwardly inclined member which is disposed within the receptacular member and with the downwardly and inwardly inclined section of its side wall defines a passage through which air travels toward the liquid in the reservoir.

8. In an air cleaner, a receptacular member which constitutes a liquid reservoir, and passages through which air enters and leaves the receptacular member, there being in the receptacular member in the path of the air which enters it a wall disposed at an angle to the vertical and above the bottom of the receptacular member.

9. In an air cleaner, an annular receptacular body, a cover for the body shaped generally like an inverted cup, an annular member in which there is provided an air inlet orifice disposed between and separable from the body and the cover, and an annular filter member which is separable from the body, the cover and the first specified member disposed between the inner wall of the body and the outer wall of the cover.

10. In an air cleaner, an annular receptacular body, a cover for the body shaped generally like an inverted cup, and an annular filter member which is separable from the body and the cover disposed between the inner wall of the former and the outer wall of the latter and clamped between the outer walls of the body and the cover, there being an orifice in the air cleaner through which air may enter the body below the cover.

11. In an air cleaner, an annular receptacular body, a cover for the body shaped generally like an inverted cup, an annular filter member which is separable from the body and the cover disposed between the inner wall of the former and the outer wall of the latter and clamped between

the outer walls of the body and the cover, there being an orifice in the air cleaner through which air may enter the body below the cover, and an annular baffle which extends from above the orifice downwardly toward the bottom of the body.

12. In an air cleaner, an annular receptacular body, a cover for the body shaped generally like an inverted cup, an annular filter member which is separable from the body and the cover disposed between the inner wall of the former and the outer wall of the latter and clamped between the outer walls of the body and the cover, there being an orifice in the air cleaner through which air may enter the body below the cover, and an annular baffle which extends from above the orifice downwardly toward the bottom of the body and has a perforate extension which extends upwardly toward the inner wall of the body.

13. In an air cleaner, an annular receptacular body, a cover for the body shaped generally like an inverted cup, an annular filter member which is separable from the body and the cover disposed between the inner wall of the former and the outer wall of the latter and clamped between the outer walls of the body and the cover, there being an orifice in the air cleaner through which air may enter the body below the cover, and annular baffles which extend from above and below the orifice downwardly toward the bottom of the body.
